COLLAPSIBLE FORM FOR CONCRETE TANKS
William J. Stovall, Rte. 2, Box 900, Silsbee, Tex.
Filed June 1, 1962, Ser. No. 205,146
6 Claims. (Cl. 25—130)

This invention comprises a novel and useful collapsible form for concrete tanks and more particularly relates to a device which will enable the construction of cylindrical tanks of concrete especially adapted for use as cisterns or septic tanks.

This application is a continuation-in-part of my prior co-pending allowed application Serial No. 808,070, filed April 22, 1959 of the same title and which is now abandoned.

Primary object of this invention is to provide a collapsible form by which cylindrical tanks of the open top monolithic type may be readily constructed.

A further object of the invention is to provide a form for making cylindrical tanks which shall be capable of quick assembly into position for receiving the cementitious material for forming a concrete tank and may be easily collapsed and stored into a very compact volume.

A further object of the invention is to provide a collapsible form having improved means for supporting, securing and retaining cylindrical inner and outer walls in properly spaced position for receiving therebetween the concrete material to form the wall of a concrete tank.

A further and more specific object of this invention is to provide a lightweight, relatively inexpensive collapsible form for constructing concrete tanks of the monolithic type having a cylindrical side wall with a bottom wall and an open top and which form may employ a relatively lightweight sheet material with means for imparting the necessary rigidity thereto in the assembled condition of the form.

Still another purpose of the unit is to provide a collapsible mold especially suitable for the fabrication of monolithic cylindrical concrete tanks of the open top type and which mold shall include pliable sheets comprising the inner and outer mold wall together with means to detachably but rigidly secure the upper and lower ends of said walls in secure and fixed relation whereby to precisely control the thickness and diameter of the top and bottom portions of the concrete tank walls.

Yet another object of the invention is the provision of a collapsible form which will enable a concrete tank to be formed in an inverted position therein.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view showing the collapsible form in accordance with this invention in its assembled or erected position in readiness for forming a concrete tank therewith, part of the cementitious material being shown broken away;

FIGURE 2 is a top plan view of the arrangement of FIGURE 1 but showing the form filled with concrete for forming a tank, and with a portion of the top of the form being broken away to show certain internal details thereof;

FIGURE 3 is a horizontal sectional view taken substantially upon the section line 3—3 of FIGURE 1 and showing a means for securing the inner wall of the form in fixed position relative to the outer wall and upon the base of the form;

FIGURE 4 is a vertical transverse sectional view taken substantially upon the plane indicated by the section line 4—4 of FIGURE 1;

2

FIGURE 5 is a perspective view of a key or locking means by which inner and outer walls of the form are secured in fixed relation to each other at their upper ends;

FIGURE 6 is a detail view in perspective showing the manner in which the ends of the outer wall of the form are detachably joined to form a single cylindrical outer wall member of the form;

FIGURE 7 is a detail view in vertical section through a portion of the structure of an inverted tank as formed by the invention;

FIGURE 8 is a perspective view of a locking means by which the two ends of the cylindrical inner wall of the form are detachably secured together; and,

FIGURE 9 is a detail view taken in vertical section upon an enlarged scale and substantially upon the plane indicated by the section line 9—9 of FIGURE 1.

It is the basic and fundamental purpose of this invention to provide a readily collapsible molding form which may be quickly and easily assembled into its operative position and by means of which monolithic cylindrical open top concrete tanks particularly adapted for use as cisterns or septic tanks and the like may be quickly and easily formed in an inverted position and may be readily removed from the form when the concrete material has hardened therein.

In accordance with this invention the collapsible concrete form indicated generally by the numeral 10 includes a base which may conveniently comprise a rigid flat circular plate or disk 12. Rigidly secured to this disk as by welding or in any other suitable manner are arcuate plate-like abutment or stop members disposed in two concentric rows. These include an outer row 14 together with an inner row 16, the inner row, however, having one member 17, see FIGURE 3, which is movably secured and mounted upon the base 12. For this purpose, the member 17 at one extremity thereof is secured to the base by a bolt 19, and adjacent its other end has secured thereto a laterally and radially inwardly projecting lug 21. A lever arm 23 is pivotally secured to the base 12 as by a pivot bolt 25 and has a short arm 27 constituting a cam element which is adapted to abut against the element 17 and swing the latter about its pivot pin 19 into the circular arrangement of the inner members 16. The other end of the lever 23 is provided with a cable or other actuating means 29, extending through a suitable opening in the base 12, by which rotation or pivoting movement may be imparted to the lever 23, as will be seen by a comparison of the solid line and dotted line showings in FIGURE 3.

The inner and outer members 16 and 14 have disposed therebetween the lower ends of the cylindrical side walls 18 and 20 of the mold form. The lower ends of the side walls rest upon the plate of the base 12 and bear against the opposed or adjacent vertical surfaces of the stop or abutment members 16 and 14 respectively, being retained therebetween by the weight or pressure of the cementitious material or concrete 30 as set forth hereinafter. It will be observed from FIGURE 4 that the upper ends of the inner and outer walls 20 and 18 are of different lengths, the upper edge of the member 18 extending upwardly beyond the upper edge of the member 20.

The inner and outer walls 20 and 18 each comprise a thin sheet of metal which is capable of readily flexing or bending. The material selected possesses the very desirable advantages of lightness of weight for handling or transportation, ease of bending to facilitate compact packaging, storing or shaping into its final contour in assembling the mold form. It has the disadvantage, however, in that it lacks sufficient rigidity in itself to secure concrete tank walls of sufficiently uniform thickness. This

last-mentioned disadvantage is effectively overcome, while all of the previously enumerated advantages are retained by providing rigid spacing and retaining means at the upper and lower ends of the walls to obtain a fixed spaced relation therebetween.

Although the weight and pressure of the concrete material may result in some outward deflection of the inner and outer walls between the upper and lower ends, resulting in a non-uniform but increased wall thickness of the concrete tank wall, this condition is not objectionable since the relatively rigid mounting and uniform spacing of the mold form walls 18 and 20 at their top and bottom edges will obtain the very desirable condition of a uniform and precisely controlled thickness of the concrete wall thickness at its top and bottom.

Later movement of the bottom edges of the walls 18 and 20 away from each other, under the pressure of the concrete material 30, is limited by their engagement with the fixed stop or abutment members 16 and 14. The upper ends are secured in fixed relation to each other by detachable fasteners or keys 22, see FIGURE 5, which each consists of a flat rigid plate-like body having a pair of parallel notches therein. A relatively shallow notch 24 is adapted to receive the upper end of the inner wall 20, while a relatively deep notch 26 embraces and receives therein the outer wall 18, as shown clearly in FIGURE 4. Thus, by the provision of a plurality of these fasteners 22, which may be individually placed wherever desired about the edges, the upper ends of the concentric walls of the form are quickly and rigidly connected to each other to provide an annular space therebetween. This permits correction to be made when the thin sheet metal walls are out of round.

The concrete material is poured or packed between the two walls 18 and 20 as shown at 30 from the top of the mold and constitutes the cylindrical wall of the tank to be formed or created by this form.

The outer wall 18 preferably consists of a single sheet of metal which is bent upon itself and its ends provided with vertical angle members 32 and 34 fixedly secured thereto as by welding or the like. Suitable fasteners 36 connect these angle members together and thus rigidly secure the sheet in a circular or cylindrical formation to form the outer wall of the tank.

The inner wall 20 likewise consists of a sheet of pliable or flexible material, which has its adjacent vertical edges provided with a plurality of vertically spaced and aligned sections of pipes or sleeves 38 welded or otherwise secured thereto. These sleeves are interdigitated as shown in FIGURE 4 so when the edges of the sheet 20 are brought together, the sleeves or pipe sections will be in vertical alignment in order that a fastening means in the form of a pin 40, see FIGURE 8, may be inserted therein to thus retain the edges together and the sheet of material in a cylindrical form to form the inner wall of the form.

As so far described it will now be apparent that the base 12 may be laid in any suitable position upon the ground, and the inner and outer sleeves 20 and 18 may then be each secured together at its ends to form a cylindrical closed wall and positioned between the abutment elements 16 and 14, thus firmly securing against lateral separation the lower ends of the inner and outer walls of the form. The upper ends are secured fixedly together in spaced relation to each other by the plates or fasteners 22 as previously mentioned.

It will now be observed from FIGURE 4 that at the upper edge of the inner wall 20 there are provided a plurality of L-shaped brackets which are welded or otherwise fixedly secured to what may be termed the inside surface of the wall 20. Each bracket, which is designated generally by the numeral 42 includes a vertical flange 44 which is welded to the inside surface of the inner wall 20 at the top edge of the same, together with a horizontal flange 46 whose top surface is disposed at

the upper edge of the inner wall 20 and extends radially inwardly of the wall 20. The series of brackets 42 constitute support means whose top surfaces support a rigid metal plate or disk 48 which rests upon the top of the bracket flanges 46 and which plate has its top surface positioned to support the mass of concrete 50 which will constitute the bottom wall of the tank. This material 50 is filled into the space bounded by the upper edge of the outer wall 18 and the plate 48, and bonds with the concrete material 30 of the wall of the tank between the fasteners 22.

In the arrangement shown in FIGURE 4 the brackets 42 are shown as being downwardly displaced from the top edge of the inner mold wall 20 so that the top surface of the plate 48 will be flush with the upper edge of the inner wall.

While the arrangement of brackets shown in FIGURE 4 is satisfactory for some uses of the invention, the arrangement shown in FIGURE 9 is generally preferred. Here the top surfaces of the horizontal flanges 46 are flush with the top edge of the inner wall 20, whereby the bottom surface of the plate 48 will be flush with the inner wall upper edge. This prevents the positioning of any concrete within the inner wall, thus facilitating collapsing of the inner wall and its removal from the molded concrete tank.

Referring now to FIGURE 7 it will now be understood that after the concrete material for the wall and bottom of the tank has been poured as at 30 and 50 and has partially set for some little time but is not yet completely hardened, the fasteners 22 may be removed. This will leave generally rectangular shaped and vertically extending slots in the concrete material 50 and 30 as shown at 52. These slots may be filled as indicated at 53 in FIGURE 7 by fresh cement being applied thereto and troweled or smoothed in place.

After the cement material has hardened the fasteners 36 may be removed and the outer wall 18 may then be stripped from the form. The form may then be turned so that the concrete tank rests upon its bottom wall 50, thereafter, the lever 23 will be released so that the member 17 may move inwardly and the base 12 may then be stripped from the side wall 30 and the fastener 40 may then be removed and the inner wall 20 may be radially contracted upon releasing the locking means 29, 23, 27, 21 and then removed. The concrete tank is then ready for use and the form is ready to be cleaned re-assembled and again used.

In some instances, tar paper or other waterproof material may be placed over the plate 48 when the latter is placed in the form upon the brackets 42 to prevent the concrete adhering thereto to facilitate removing of this plate after the concrete has set and hardened into the complete tank.

It will be further understood that in some instances it may be preferred to form the base 12 as an annulus or ring rather than as a solid disk both to lighten the weight of the same and to also facilitate entry into the interior of the form as for example in order to apply or remove the fastener 40 and also have access to the lever 23 and its actuating cable 29 by means of which the movable stop or abutment member 17 is locked into proper position for holding the inner wall in place and for being moved to a position to release the same and permit easy removal of the inner wall.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A collapsible form for making concrete tanks com-

prising a base and a pair of concentric inner and outer walls mounted upon said base at their lower edges, circumferentially spaced upstanding means on said base maintaining the lower ends of said walls in fixed spaced relation upon said base, fasteners securing the upper edges of said walls in fixed spaced relation whereby they may receive and retain therebetween concrete to form the wall of a tank, a plate disposed on the inner wall and below the upper end of the outer wall and cooperating with the latter to support concrete to form the bottom of a tank, support means carried by said inner wall for mounting said plate, said maintaining means comprising inner and outer abutment elements consisting of arcuate blocks fixedly mounted on and projecting upwardly from said base in concentric circles, the lower edges of said walls being received between said inner and outer abutment elements and being engaged and prevented from separation thereby, the blocks of the inner circle including an arcuate element pivoted to said base, a lever pivoted to said base, and having a cam surface engaging said arcuate element for releasably locking the latter into retaining engagement with said inner wall.

2. The combination of claim 1 wherein said fasteners each consist of a vertically extending rigid plate having a pair of notches projecting upwardly from its lower edge, the notches being of different vertical extent with the top edges of said inner and outer walls being received respectively in the shallower and deeper of said notches respectively, said fasteners having vertical edges disposed inwardly of said inner wall and engaging the periphery of said plate for positioning the latter centrally of said inner wall.

3. The combination of claim 1 wherein said fasteners comprise a series of manually engageable locking keys individually positionable upon said inner and outer walls at selective circumferentially spaced positions thereon, each key comprising a rigid, vertically extending metallic plate, said plate having a lower edge with a pair of notches extending upwardly from said lower edge to different vertical heights in said plate whereby to seat and rigidly retain in fixed spaced relation the adjacent portions of the upper edges of said inner and outer walls.

4. The combination of claim 1 wherein each wall consists of a single piece of a pliable and readily bendable sheet metal whereby it may be easily collapsed and

5 compactly folded for storage, said base plate and fasteners being of a rigid material whereby to stiffen said sheet metal in their assembled relation and maintain the upper and lower edges of the sheets in fixed relation to each other and against inward collapse.

10 5. A collapsible form for making concrete tanks comprising a base and a pair of concentric inner and outer walls mounted upon said base at their lower edges, circumferentially spaced upstanding means on said base maintaining the lower ends of said walls in fixed spaced relation upon said base, fasteners securing the upper edges of said walls in fixed spaced relation whereby they may receive and retain therebetween concrete to form the wall of a tank, a plate disposed on the inner wall and below the upper end of the outer wall and cooperating with the latter to support concrete to form the bottom of a tank, support means carried by said inner wall for mounting said plate, said maintaining means comprising inner and outer abutment elements consisting of arcuate blocks fixedly mounted on and projecting upwardly from said base in concentric circles, the lower edges of said walls being received between said inner and outer abutment elements and being engaged and prevented from separation thereby, the blocks of the inner circle including an arcuate element pivoted to said base, means movably mounted on said base and engaging said arcuate element for releasably locking the latter into retaining engagement with said inner wall.

20 6. The combination of claim 5 wherein said support means include a plurality of circumferentially spaced support brackets secured to and projecting inwardly from the inner wall adjacent its upper edge, said plate being rigid and being carried by the inner wall at its upper edge, said brackets constituting both a support for said plate and a stiffener for said inner wall, said plate having its periphery engageable with said fasteners whereby said plate will prevent inward collapse of the upper ends of said walls.
